SHELDON CARY AND SPENCER C. CARY, OF NEW YORK, N. Y.

Letters Patent No. 76,994, dated April 21, 1868.

IMPROVED BOTTLE-STOPPER.

The Schedule referred to in these Letters Patent and making part of the same.

TO ALL WHOM IT MAY CONCERN:

Be it known that we, SHELDON CARY and SPENCER C. CARY, of the city, county, and State of New York, have invented a new and improved Bottle-Stopper; and we do hereby declare that the following is a full, clear, and exact description thereof, which will enable others skilled in the art to make and use the same, reference being had to the accompanying drawings, forming part of this specification, in which—

Figure 1 represents a side view, partly in section, of our improved bottle-stopper.

Figure 2 is an inverted plan view of the same.

Similar letters of reference indicate corresponding parts.

This invention relates to a new manner of strengthening and protecting cork bottle-stoppers, and consists in the use of a cap, made of metal foil, fitted around and over the upper part of the cork. The cork is thereby not only made air-tight, so as to form an air-tight stopper for the bottle, but it is also made stronger, and not so liable to crumble. The metal foil increases the diameter of the stopper so little that it will fit easily into the mouth of a bottle, if it did fit without the cap.

A, in the drawing, represents a cork stopper, of suitable shape. B is a metal-foil cap, placed around and over the upper part of the cork, as shown. The upper end of the cap may also be covered by a sheet-metal plate, C, which projects beyond the sides of the stopper, so as to prevent the same from being forced too deep into the bottle.

The plate C is fastened to the cap B, either by clamping it, as at a, or by fitting with its turned-in edge tight against it, as at b in fig. 1. The invention is applicable to jar and can-stoppers as well as to bottles.

We are aware that elastic caps have already been used on corks, but the same were only for the purpose of making the cork water or air-tight, and they did not strengthen the stopper, as is done by the metallic cap. Moreover, they had to be made thick to be of service, and they were then too thick to allow the lower end of the cork to be of any use, or too long, to the injury of the contents of the bottle, while our metallic-foil cap is so thin that it overcomes the aforesaid inconveniences.

The stopper must not fit so tightly in the neck of the bottle that the metallic foil can be rubbed off; therefore a shoulder is required to sustain the stopper. The projecting flat plate, on the top of the stopper, forms a shoulder for this purpose.

Having described our invention, we claim as new, and desire to secure by Letters Patent—

As a new article of manufacture, a bottle-stopper, provided with a cap, B, of metallic foil, and a flat plate, C, which projects over the edges of the stopper, whereby said stopper is prevented from being forced too far into the neck of the bottle, as described.

SHELDON CARY,
SPENCER C. CARY.
